UNITED STATES PATENT OFFICE.

GEORGE LINTON HOFFER, OF LAUREL, MISSISSIPPI.

CAR-BRASS MOLD.

956,638.

Specification of Letters Patent.

Patented May 3, 1910.

Application filed March 3, 1909. Serial No. 481,093.

To all whom it may concern:

Be it known that I, GEORGE L. HOFFER, a citizen of the United States, residing at Laurel, in the county of Jones and State of Mississippi, have invented a new and useful Car-Brass Mold, of which the following is a specification.

The principal object of the present invention is to provide an improved mold for casting journal bearings or brasses for car wheel axles to the end that a large number of brasses may be manufactured in a short time.

A further object of the invention is to provide a novel form of mold in which any desired number of sections may be assembled together, the sections being of precisely the same construction and so arranged that one face of each section shall form the back of the brass while the opposite face of the same section shall form the concave journal receiving face of another brass.

A still further object of the invention is to provide a mold of this type in which the mold sections are provided with interchangeable members for forming the concave journal receiving faces so that brasses of the ordinary Master Car Builders' type, or self-oiling, or lead-lined brasses may be made as desired.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings:—Figure 1 is a longitudinal sectional view illustrating a number of mold sections assembled in readiness for the casting operation. Fig. 2 is a sectional plan view of the same. Fig. 3 is a sectional plan view of one of the sections showing the same fitted in readiness for the casting of a self-oiling brass. Fig. 4 is a similar view showing the mold section adjusted in readiness for the casting of a lead-lined brass. Fig. 5 is a detail perspective view looking at one face of the mold section. Fig. 6 is a similar view looking at the opposite face thereof. Fig. 7 is a detail

perspective view of the convex section employed in the molding of self-oiling brasses. Figs. 8 and 9 are detail views of the members used in the molding of lead-lined brasses. 60

Similar numerals of reference are employed to indicate the corresponding parts throughout the several figures of the drawings.

Each of the main sections of which the multiple mold is built up is of precisely the same construction being of generally rectangular contour and provided with a vertical central web 10 of practically uniform thickness except at the top where it is recessed as indicated at 11 to form the rib which is arranged at the end of the brass and in practice is disposed at that end of the brass adjacent the car wheel. The inner or molding surface of the web has small ribs 13 to form a panel which may contain a name plate or other identifying marks, and preferably there are a pair of small lugs 14 which extend from the web near the upper and lower ends thereof to form oil passages 75 in the brass, although these are not essential. At the opposite sides of the central web the walls are much thicker as indicated at 14' and the inner faces of these walls are disposed at an angle to each other in order 80 to form the angular upper faces of the brass. These walls also are recessed as indicated at 16 in alignment with the recess 11 to form the end rib of the brass. On one of the walls 14' of this face of the molding section, which 85 for convenience may be termed the rear face, is a projecting rib 17 that extends from the top of the section down to a point adjacent the lower end thereof and there terminates in an abrupt horizontal shoulder 18 that 90 extends back to the plane of the rear wall of the rib 15.

The rib 17 as shown more clearly in Fig. 6 is provided with a number of recesses 20 which, as will be readily recognized, follow 100 the general contour of the side webs of the Master Car Builders' brass. The opposite rib 15 is provided on its rear face with a lug 21 that extends rearward from the upper end of the section and projects outward to 105 a point in alignment with the rear face of the rib 17.

The front face of each section is flat as indicated at 23 in Fig. 5, and at one side is a forwardly projecting rib 24 of a thickness 110 corresponding to the thickness of the lug 21 and having its top terminating in an ab-

rupt horizontal shoulder 25 that is arranged to engage a similar shoulder 26 at the base of the lug 21 of the next adjacent section. The inner-most or active face of the rib 24 is provided with recesses 27 corresponding to the contour of the side web of the brass. Projecting from the face 23 of the section is a lug 28 which will extend partly into the large central recess 20 formed in the rib 17 and will coöperate with the walls of the latter in shaping the side webs, while a corresponding lug 29, formed at the inner face of the rib 24 shapes the opposite side of the brass. Projecting from the bottom of the face 23 of each section is a plate 31 in the form of a flange, the outer edge of which conforms to the angular rear face of the next adjacent section and the thickness of this flange is such that the lower shoulder 18 of the flange 17 of the next adjacent section will rest thereagainst. The flange 31 of each section will form the bottom of the mold and will also serve in part as a support for the next adjacent section in that it receives the shoulder 18 at the bottom of flange 17 of said next adjacent section, while at the same time the shoulder 26 of the lug 21 of said adjacent section will rest against the top shoulder 25 of the flange 24 of the first section. Secured to the flat front face of each section is a convex member 36 which may be provided with suitable fastening devices, as, for instance, pins 37 which enter corresponding sockets in the flat face referred to, and this member 36 is provided at the top with a forwardly projecting lug 38, the inner face of which is provided with a tapered groove 39 which in combination with the tapered opening 40 at the top of each of the main sections constitute a pouring gate through which the molten brass is poured in the casting operation.

The rear face of each of the members 36 is provided at the top with a concaved recess 41 which also forms a part of the gate running into the next adjacent mold so that the members 36 will in effect form partitions to separate the several gates from each other. The section 36 shown in Figs. 1 and 2 is provided with a smooth curved surface forming part of a cylinder and of a shape corresponding to the concave face that receives the journal of the car axle.

Where it is desired to form a concave face having grooves, that is to say to cast a self-oiling brass, the section 36^a of the type shown in Figs. 3 and 7 is substituted for the section 36. The member 36^a is of the same general contour as the member 36 except that its convex face is provided with a plurality of ribs 44 running in slightly helical lines and intersected by a longitudinal rib 45 that extends downward from the gateway lug 38^a. These ribs form grooves in the bearing surface of the brass in order to per-

mit ready feeding and passage of the lubricant. To make other type of self-oiling bearings, that is to say, bearings in which the brasses are provided with perforations extending entirely therethrough, a number 70 of tapered blocks 47 may be attached to the back face of each section, as indicated in Fig. 6.

Where it is desired to form a lead-lined brass a number of sections 36^b, 36^c are substituted for the section 36 and these form the inner face of the brass of a substantially triangular contour and provide a relatively deep rib as shown in Fig. 4, the dotted lines in this case representing approximately the 80 cross sectional contour of the brass before the application of the lead.

After the brass has been cast, removed from the mold, and the gate cut away in the usual manner, the brass is placed in a mold 85 having the cylindrical member 36 in place and there will then be a space between the inner face of the brass and the convex face of the member 36, and this is filled with lead, Babbitt metal or other composition. 90

While the several sections 36, 36^a, etc., have been described as removable and interchangeable it is obvious that they may be cast or otherwise formed integral with the sections where numbers of brasses of precisely the same type are to be made. 95

In practice any number of mold sections are assembled together in the manner shown in Figs. 1 and 2 and each has its independent gate through which the brass is poured. 100 The sections are held from independent vertical and lateral play by reason of their interfitting parts, while the spreading of the sections on the entrance of the molten metal may be prevented by the employment 105 of any of the clamping devices ordinarily used for holding mold sections together.

What is claimed is:—

1. In a mold of the class described, a series of like sections each having two opposite molding faces and provided with an interchangeable member on one of said faces for the formation of the concave faces of car brasses, said members being provided at their upper ends with lugs shaped to 110 form portions of the gates.

2. A mold section having a central vertical web, the rear face of the section at opposite sides of the web being provided with inclined faces, the rear face of the web and 120 the corresponding or alining portions of the faces being recessed, one of said faces having a projecting rib that terminates short of the bottom of the section and the other face being provided at the top with a projecting lug, the front face of each section having at the bottom an angular flange arranged to fit within the angular rear face of an adjacent section, one side of the front face being provided with a flange adapted to 125 130

fit against the lug of a mating section, and an auxiliary member arranged to fit against the front face of the web and to shape the concave face of the brass, the auxiliary 5 member and the upper end of the central web being shaped to form independent gate-ways to adjacent mold spaces.

3. A movable mold formed of a series of like nesting sections having two opposite 10 molding faces and provided with interfitting ribs projecting from both said faces and each having an extension at its upper end, and a shaping member secured to the front face of each section and having a vertical lug at its upper end to bear against the 15 extension of the upper end of the section and to coact therewith to provide gate-ways to the adjacent molding spaces.

4. A mold section having a central, vertical web, the rear face of the section at opposite sides of the web being provided with inclined faces, the rear face of the web and

the corresponding or alining portions of the faces being recessed, one of said faces having a projecting rib that terminates short of 25 the bottom of the section and the other face being provided at the top with a projecting lug, the front face of each section having at the bottom an angular flange arranged to fit within the angular rear face of an adjacent 30 section, one side of the front face being provided with a flange adapted to fit against the lug of a mating section, and the upper end of the central web being shaped to form independent gateways to adjacent mold 35 spaces.

In testimony that I claim the foregoing as my own, I have hereto affixed my signature in the presence of two witnesses.
